UNITED STATES PATENT OFFICE.

LOUIS M. MUSLINER, OF NEW YORK, N. Y., ASSIGNOR TO GEISMAN & MUSLINER, OF NEW YORK, N. Y., A COPARTNERSHIP.

DESIGN FOR EMBOSSED FABRIC.

No. 38,060.

Specification for Design.

Patented June 5, 1906.

Application filed March 12, 1906. Serial No. 305,723. Term of patent 7 years.

To all whom it may concern:

Be it known that I, LOUIS M. MUSLINER, a citizen of the United States, residing in the city, county, and State of New York, have invented a new, original, and ornamental Design for Embossed Fabric, of which the following is a specification, reference being had to the accompanying drawing, forming a part thereof.

The figure is a view of a piece of embossed fabric, showing my new design.

I claim—

The ornamental design for embossed fabric, as shown.

LOUIS M. MUSLINER.
